UNITED STATES PATENT OFFICE.

WALKER H. SPAYD AND FRED M. SPAYD, OF VAN WERT, OHIO.

VALVE MECHANISM.

No. 927,694.

Specification of Letters Patent.

Patented July 13, 1909.

Application filed April 16, 1908. Serial No. 427,436.

To all whom it may concern:

Be it known that we, WALKER H. SPAYD and FRED M. SPAYD, citizens of the United States, residing at Van Wert, in the county 5 of Van Wert and State of Ohio, have invented certain new and useful Improvements in Valve Mechanism; and we do declare the following to be a full, clear, and exact description of the invention, such as will enable 10 others skilled in the art to which it appertains to make and use the same.

Our invention relates to valve mechanisms, and particularly to valve mechanisms employed in operating the exhaust of explosion engines.

The object of the invention is to provide a simple, cheap and efficient valve gear for operating the exhaust valve of four cycle explosive engines.

20 A further object is to provide simple means to disconnect the exhaust valve operating rod whereby upon the compression stroke of the engine the exhaust valve remains closed, and further means controlled by the 25 ignition circuit for throwing the valve mechanisms into action upon the exhaust or scavenging stroke of the engine.

With these and other objects in view, the 30 invention consists of certain novel features of construction, combination and arrangement of parts, which will be more fully described and particularly pointed out in the appended claims.

In the drawings, Figure 1 is a side elevation partly in section, showing the position 35 of the parts at the beginning of the compression stroke; Fig. 2 is a transverse sectional view taken on the line $\alpha-\alpha$ of Fig. 1; Fig. 3 is a diagrammatic view, in side elevation, showing the parts in the same position 40 as in Fig. 1 and the relation between the valve gear magnet and the engine shaft.

Referring more especially to the drawings, 45 1 represents an explosion engine, and 2 an exhaust valve port leading from the chamber to the exhaust pipe 3. Secured to the cylinder in any suitable manner is a casing 4, in which is slidably mounted the exhaust valve rod 5 carrying at its outer end the exhaust 50 valve 6, adapted to close the port 2. This rod is slidably mounted between the top of the casing 4, and a horizontal rib 7, formed on one side of the casing so as to form a guide for and prevent any vertical or lateral 55 swinging of the rod. Sliding in the casing in an opposite direction from the rod 5 is a

rod operating link 8, provided with knuckle 9, which enters the bifurcated end of the cone rod 10. This rod 10 is provided at its outer end with a friction roller 11, which 60 engages a cam 12, keyed to the driving shaft 13, of the engine. A suitable spring 14 holds the valve 6 upon its seat, and a spring 15 maintains the friction roller 11 in engagement with the eccentric. The inner end of 65 the rod 5 is beveled and notched as at 16, and the inner end of the link 8 is oppositely beveled and notched as at 17, so as to properly engage the beveled and notched edge of the rod 5.

70 Pivoted to the sides of the frame upon a transversely extending bolt 18, is a trigger 19, controlled by a spring 20, which normally throws the trigger upward to its limit. A spring arm 21, extends out from the rear 75 end of the trigger and engages the corner of the casing and flexibly limits the movement of the trigger. At certain periods during the operation the trigger is adapted to engage a notch 22 formed in the upper edge 80 of the link for a purpose which will be hereinafter described.

Depending from a pair of lugs 23, formed integral with the side of the casing is a supporting arm 24, having positioned upon its 85 outer end an electromagnet 25, whose armature 26 is carried upon the forward end of a lever 27, pivoted between the sides of the casing and carrying at its rear end a friction roller 28, adapted to engage the under side 90 of the link 8 to force it up against the top of the casing.

In Fig. 2 we have illustrated a simple way to operate the magnet 25. This consists in keying to the driving shaft a pinion 29 95 which operates a gear 30 of twice its size carried upon a shaft 31 upon which there is also a wiping cam 32. This cam is adapted to wipe against the spring contact finger 33 of the switch S so as to force it into engagement with the anvil contact and closes the primary circuit of the spark coil S'. The primary of this spark coil is inclined in circuit with a suitable battery B and a switch S² together with the magnet 25. The 100 secondary of the coil has its terminals connected directly to the opposite points upon the spark plug P. As the cam 31 rotates once for every two revolutions of the cam 12 and is slightly advanced thereover it will be 105 noticed that by following out the order of strokes the cam only wipes into contact 110

with the spring finger 33 at each compression stroke of the engine, or upon every four strokes of the piston. As engines of the four cycle type only receive one explosion for every two revolutions of the fly wheel it is necessary that the exhaust mechanism be operated only during the stroke immediately after the power stroke and that it should not be open during the suction or compression strokes of the engine, and only during a partial portion of the scavenging stroke. In order to accomplish this we position the cam disk 12 so that it operates upon the cam rod 10 and the link 8 in such a manner that the end 17 when in engagement with the end 16 carries the valve forward and holds the port open until the greater part of the scavenging stroke has been completed. When the springs 14 and 15 return the parts to normal and before the lower side of the cam disk 12 is reached the notch 32 is engaged by the forward end of the trigger and depresses the inner end 17 of the link 8 away from the valve rod 16, thus disconnecting the parts and allowing the link 8, upon the next or compression stroke of the engine to pass beneath the rod 5 without engaging it. When, however, the sparker mechanism is operated by the cam 32, the magnet 25, which is included in the primary circuit thereof is energized to throw the friction wheel 28 into engagement with the link 8 and force it up into the path of the rod 5. As the trigger 19 has already been released from the notch 22 upon the suction stroke and forced to normal by the spring 20 the link 8 is free to rise to the top of the casing. The spring arm 21 retains the point of the trigger sufficiently far below the top of the case so that it will engage the notch 22 when the link 8 is retracted and permits it to be forced upward by the link until the notch is reached, when the spring arm 21 overcomes the spring 20 and throws the engaging point into the notch.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described our invention what we claim and desire to secure by Letters Patent is:—

1. In a valve mechanism for explosion engines, the combination with a valve, of means to operate the valve rod, means controlled by the sparker circuit of the engine to throw said valve operating means into operative position, and means to render said valve operating means inoperative.

2. In a valve operating mechanism for explosion engines, a valve, a pivoted link adapted to engage the valve rod, means controlled by the engine for operating said link, means controlled by the sparker circuit of the engine for throwing said link into engagement with the valve rod, means for reciprocating said link, and means for throwing said link out of engagement with the valve rod and holding it in such position for a predetermined time.

3. In a valve mechanism for explosion engines, the combination with a valve, of a power shaft having a cam thereon, a rod driven by said cam, a link pivoted to said rod adapted to engage said valve rod to open the valve aforesaid, an electromagnet in series with the sparker circuit, means controlled by said magnet for throwing the link into engagement with the valve rod, and a trigger adapted to engage the link upon retrograde movement of the rod to break the connection of the link with the valve rod and to hold said link in inoperative position during the next forward movement thereof.

In testimony whereof we have hereunto set our hands in presence of two subscribing witnesses.

WALKER H. SPAYD.
FRED M. SPAYD.
